UNITED STATES PATENT OFFICE.

WALTER PINELL, OF BERLIN, GERMANY, ASSIGNOR TO SIEMENS & HALSKE AKTIEN-
GESELLSCHAFT, WERNERWERK, OF SIEMENSSTADT, NEAR BERLIN, GERMANY.

AUTOMATIC TELEPHONE SYSTEM.

Application filed June 13, 1927, Serial No. 198,845, and in Germany October 12, 1926.

The present invention relates to a circuit arrangement for testing relays in telephone circuits, particularly those employing selectors. Known already are arrangements in which in order to obtain a short period of response, testing relays are premagnetized by special auxiliary means. According to the present invention these latter are now avoided in that, before the commencement of a test (for instance, when the selector is engaged), the energizing winding of the testing relay is placed in circuit by switching means, so that the said relay may be premagnetized.

15 The present invention is shown in the attached drawing, but the invention is not limited to this example, and can be applied to all kinds of stepping switch mechanisms, such as preselector devices, second group 20 selectors and line selectors. If, in the present example, a first group selector GW is engaged by a pre-selector, then the relays A, B, and C respond. The relay A actuates its alternating contact a and the relay C 25 its contacts c^1 and c^2 . The relay C closes a holding circuit for itself over: Earth, winding of relay V^1 , alternating contact a , winding II of the relay C, contact a^1 , battery, earth.

30 In this circuit, the relay V^1 is also energized and the contacts $1v^1$, $2v^1$, $3v^1$, and $4v^1$ are thrown over. Over the contact $1v^1$ the following circuit is now closed: Earth, battery, resistance W, contact $1v^1$, winding 35 II of the relay P, earth.

The winding II of the relay P receives the current, and, according to the invention, through this winding, the testing relay P is premagnetized before the commencement 40 of the test over the contact $1v^1$. On account of the resistance W the winding II of the testing relay P does not receive enough current to cause relay P to operate its contacts p . By sending out the first series of 45 impulses on the part of the calling subscriber, the group selector GW is set to the number tens level. The relays A and B, during the sending out of the impulse series, are energized and deenergized in accordance with the current impulses and repeat the impulses to the stepping relay J. The battery feed supply to the calling subscriber's station is also made over the relays A and B. The current impulses are transmitted to the relay J over the following

route: Battery, earth, winding of the relay J, back contact a^2 , contact $4v^1$, earth.

The lifting magnet H of the group selector GW receives the current impulses sent out over the contact i^2 . During the sending out of current impulses the relays C, V^1 and V ^{2} remain energized.

After the termination of the impulse series the relay V^2 deenergizes; thus, it is in working position from the beginning up to the end of the impulse series. During the first lifting step the vertical off normal contact k^1 is opened and vertical off-normal contacts k^2 and k^3 are closed. The winding I of the relay C is deprived of current due to the opening of the contact k^1 but the relay holds itself over its winding II. The group selector GW is maintained busy by earth being applied over contact c^2 , resistance W ^{1} , releasing contact m to the testing wire of the group selector GW. After the sending of the first impulse series and the closing of the off-normal contact k^2 , the following circuit is established for the rotary magnet D: Contact k^2 , back contact p^5 , back contact $1v^2$, contact $2v^1$, back contact i^1 , winding of the rotary magnet D, battery, earth. By hunting the group selector GW now seeks a junction line leading to the next impulse register. Upon the rotary magnet D functioning, the alternating contact d is thrown over, so that the relay J is made to respond over this circuit: Earth, alternating contact d , winding of the relay J, battery, earth.

The circuit for the lifting magnet H is interrupted by the opening of the rotary off normal shaft contact RON. When the relay J responds the circuit for the rotary magnet d is broken through the back contact i^1 , and when the rotary magnet d deenergizes, the circuit for the relay J is opened by the alternating contact d and the relay J deenergizes. This alternating action between the relay J and the rotary magnet D continues until a free junction line is found and the circuit for the rotary magnet d is broken over the back contact p^5 .

When an idle junction line and switch is found, then the relay P responds over the following circuit: Earth, battery, (on the incoming test lead of the idle switch), switching arm c of the group selector, winding I of the relay P, alternating contact $1v^1$, winding II of the relay P, earth.

The testing relay P responds very rapidly, because, according to the invention, the testing relay P is provided with a pre-magnetized winding, viz, the winding II. As already described, the winding I of the relay P receives current due to the functioning of the relay V¹. The energizing winding of the relay P (winding II) is, at the same time, the premagnetizing winding for the testing relay P. After the functioning of the latter, a holding circuit is closed for the same, viz, over: Earth, contact p³, winding I of the testing relay P, (holding winding of the testing relay), contact arm e, test wire, battery, earth, (in the seized switch).

The speaking wires a and b are switched through over the contacts p¹ and p². After the conclusion of a call the group selector GW is released in the following manner. Relay A deenergizes when the calling subscriber hangs up and said relay at contact a short circuits relay C whereupon the latter relay after an interval deenergizes. Relay C, upon deenergizing, opens the circuit of relays V¹ and V² which deenergize and complete a circuit for operating the release magnet M. At contact e² and m the holding circuit to the preceding switch is opened. The releasing magnet of the group selector receives current over the following path: Earth, battery, winding of the releasing magnet M, back contact 3v¹, back contact 3v², back contact p⁴, off-normal contact k³, earth.

What is claimed is:

1. In an automatic switch, a test relay, a switching device, and means controlled by said switching device for pre-magnetizing but not operating said test relay responsive to the seizure of said switch in order to assist said relay to operate when an idle line is encountered by said switch.

2. In a telephone system, an automatic switch, trunk lines accessible to said switch, a test relay in said switch adapted to be energized to seize one of said trunk lines, a switching device in said switch, means controlled by said device for pre-magnetizing said test relay responsive to the seizure of said switch, means for operating said switch to test said trunk lines, and means for

operating said relay responsive to said switch encountering an idle one of said trunk lines, said pre-magnetization effective to assist in the operation of said relay.

3. In an automatic switch having access to trunk lines, a test relay having two windings, means responsive to the seizure of said switch for premagnetizing said relay over one of its windings, means for operating said switch to test for an idle one of said trunk lines, and a circuit for energizing said relay including the test lead of an idle trunk and the two windings of said relay in series.

4. In an automatic switch having access to trunk lines, a test relay having two windings, one of said windings being normally short circuited, means responsive to the seizure of said switch for opening the short circuit around said first winding and for closing a circuit to pre-magnetize said second winding, means for operating said switch to test for an idle one of said trunk lines, and a circuit for energizing said relay including the test lead of an idle trunk and the two windings of said relay in series.

5. In an automatic switch, a test relay, line wipers, a pair of talking conductors, contacts on said relay normally disconnecting said conductors from said wipers, a switching device, means controlled by said device for pre-magnetizing said relay responsive to the seizure of said switch, and means for energizing said relay to operate said contacts to connect said conductors with said wipers.

6. In a telephone system, an automatic switch, trunk lines accessible to said switch, a test relay in said switch, a switching device in said switch, means controlled by said device for pre-magnetizing said relay responsive to the seizure of said switch, means for operating said switch to test said trunk lines, means for energizing said relay responsive to said switch encountering an idle one of said trunk lines, and contacts on said relay for connecting a busy potential to the test contact of the seized trunk line.

In witness whereof, I hereunto subscribe my name this 11th day of May, A. D. 1927.

WALTER PINELL.
